(57) **CLAIM**

The ornamental design for a motor vehicle body, toy vehicle body replica and/or other replica, as shown and described.

DESCRIPTION

This application contains subject matter related to the following co-pending U.S. design patent application:

Application Ser. No. 29/777,716, filed Apr. 8, 2021 and entitled “Motor Vehicle Body, Toy Replica, and/or Other Replica.”

FIG. 1 is a left, front perspective view of a motor vehicle body, toy vehicle body replica and/or other replica showing my new design;

FIG. 2 is a left, rear perspective view thereof;

FIG. 3 is a front view thereof;

FIG. 4 is a rear view thereof;

FIG. 5 is a right side view thereof;

FIG. 6 is a left side view thereof; and,

FIG. 7 is a top view thereof.

The broken lines shown throughout the drawing views are for environmental and illustrative purposes that form no part of the claimed design.

1 Claim, 7 Drawing Sheets
